UNITED STATES PATENT OFFICE.

JOHN P. McCALLUS, OF WEATHERLY, PENNSYLVANIA.

VALVE SILENCER.

1,424,205.

Specification of Letters Patent. Patented Aug. 1, 1922.

Application filed March 31, 1921. Serial No. 457,563.

To all whom it may concern:

Be it known that I, JOHN P. McCALLUS, a citizen of the United States of America, residing at Weatherly, in the county of Carbon and State of Pennsylvania, have invented certain new and useful Improvements in Valve Silencers, of which the following is a specification.

This invention relates to certain new and useful improvements in valve silencers and more particularly relates to an improved attachment for the tappet rods or valve operating mechanism whereby the objectionable chattering and like noises are prevented which occur incident to wear between the contacting parts of the valve stem and tappet rod, and between the tappet rod and its mounting sleeve.

Briefly described, the invention comprises a piece of metal formed for rigid attachment to the adjusting bolt of the tappet rod and including depending legs arranged to frictionally engage the engine casing or frame at opposite sides of the tappet rod. The depending fingers are resilient so as to prevent rattling of the tappet rod within its mounting sleeve and, by engaging the engine casing at opposite sides of the tappet rod turning of the latter is prevented so as to insure proper engagement between the lower end of the tappet rod and its actuating cam. The friction between the depending legs of the attachment and the engine casing prevents downward movement of the tappet rod beyond the downward movement to which it is pressed by the valve stem so that, at no time, is there any play between the tappet rod and the valve stem for producing the objectionable knocking between these parts.

With the above general objects in view and others that will become apparent as the nature of the invention is better understood, the same consists in the novel form, combination and arrangement of parts hereinafter more fully described and shown in the accompanying drawing, in which like reference characters indicate corresponding parts throughout the several views.

50 In the drawing,

Figure 1 is a fragmentary elevational view of an engine with its valve operating mechanism equipped with a valve silencer constructed in accordance with the present invention,

55 Figure 2 is a horizontal sectional view

taken substantially upon line II—II of Figure 1 and drawn on a larger scale,

Figure 3 is a vertical sectional view taken substantially upon line III—III of Figure 60 1 and drawn on a larger scale, and

Figure 4 is an enlarged perspective view of the valve silencing attachment removed.

In the drawing, the numeral 5 indicates in general the cylinder of a gas engine and 65 6, a valve casing associated therewith. The valve casing is provided with a seat 7 for the valve which is indicated by the numeral 8, and which has a stem 9 working in a suitable bushing 10 fitted through the lower end 70 of the valve casing. A spring 11 bears at its upper end against the lower end of the valve casing and at its lower end against a suitable stop 12 upon said stem, and this spring tends to lower the valve to its seat. 75 The oil containing crank case of the engine is indicated at 13, and working in the same is a cam shaft 14 carrying the actuating cam 15 for the valve, said cam being designed to coact with the push rod, which latter in turn, 80 coacts with the lower end of the valve stem as will now be explained.

The push rod usually includes a cylindrical member 16 having a roller 17 journaled on the lower end thereof for engagement 85 with the cam 15 and said cylindrical member 16 is mounted for vertical sliding movement through the top of the crank case 13 and in a removable sleeve 18 carried thereby. The cylindrical member 16 is also provided 90 with a threaded bore 19 in its upper end adjustably receiving an abutment screw 20 which is held at adjustment by means of a jamb nut 21 threaded thereon and usually bearing against the upper end of the section 95 16. As clearly shown in the drawing, the lower end of the valve stem 9 rests upon the head of the abutment screw 20 in both the open and closed positions of the valve until wear takes place between this screw and the 100 valve stem when play is permitted between the same and consequently causes an objectionable hammering noise. Also, the member 16 is likely to turn so that the roller 17 does not properly engage the cam 15 and 105 in addition to this the wear which takes place between the member 16 and its mounting sleeve 18 permits a rattling noise between these parts.

The above construction is old and com- 110 monly found in use and the present device is designed to eliminate this hammering and

rattling noise and to also prevent turning of the member 16 of the tappet rod.

This is accomplished by means of a simple form of attachment clearly shown in Figure 4 which consists of a single piece of metal with a plate portion 22 having a central opening 23 for reception of the shank of the abutment screw 20 whereby said plate portion is rigidly clamped against turning between the jamb nut 21 and the upper end of the tappet rod member 16. The attachment also includes a pair of resilient legs 24 which extend at right angles from the plate portion 22 and from opposite ends of the latter so as to frictionally engage the vertical face 25 of the engine casing. Thus, the legs 24 depend so as to flatly engage said face 25 at opposite sides of the sleeve 18 and the tappet rod carried thereby so that turning of the tappet rod is prevented while the frictional engagement of the legs with the engine casing prevents the tappet rod from lowering further than the same is positively moved by means of the stem 9 of the valve 8 when the latter is seated by means of the spring 11. In this way, contact is insured between the abutment screw 20 and the valve stem 9 so as to prevent hammering between these parts and the resilient nature of the legs 24 prevents such movement of the tappet member 16 as would cause rattling of the same against the sleeve 18. It will be noted that the present attachment does not serve

as a spring for holding the tappet rod upwardly against the lower end of the valve stem but merely prevents movement of the tappet downwardly by gravity further than the same is forced by the valve stem and its closing spring 11.

It will thus be seen that the present invention provides an improved and efficient means for the designated functions and which may be easily and cheaply manufactured as well as readily placed into use. Minor changes may be made without departing from the spirit and scope of the invention as claimed.

What is claimed as new is:

A valve silencing attachment for tappet rods comprising a piece of sheet metal including a plate portion with a central opening for reception of the abutment screw of the tappet rod whereby the device may be rigidly clamped against the upper end of the tappet rod by the jamb nut of said abutment screw, and depending resilient legs carried by said plate portion and disposed to frictionally engage the adjacent vertical face of the engine casing, said legs being of lesser length than said vertical face whereby the entire attachment may bodily move vertically with the tappet rod with only frictional resistance to such movement.

In testimony whereof I affix my signature.

JOHN P. McCALLUS.
